ARNOLD AUGUST EGLI, OF HAMBURG, GERMANY

MULTICOLOR INTAGLIO PRINTING MACHINE

Application filed September 22, 1928, Serial No. 307,730, and in Germany September 26, 1927.

In the known multi-color sheet intaglio printing machine in which two or more printing cylinders, which are arranged around an impression cylinder having several impression surfaces, operate simultaneously on different impression surfaces of the impression cylinder, the printing cylinders begin to operate in turns, so that, while the printing by one printing cylinder is proceeding, the impression cylinder is itself shaken owing to another printing cylinder beginning to print later; this shaking cannot be avoided, however heavy the bearings of the impression cylinder may be, because the elasticity of the body of the impression cylinder itself allows some vibration to occur to an extent which gives rise to the difficulties hereinafter described. The print consists in fact of microscopically small points and lines. The slightest vibration causes the dimensions of these points and lines to be altered, so that a print which is different from that intended is produced, and in particular light and dark strips of shading are formed so that the value of the print is reduced. As is known these appearances of shading are called tooth-strips in mechanical book presses, offset and lithographic printing machines, because they occur in these machines owing to the shaking caused by the engagement of the teeth. The present invention overcomes all these difficulties of the known arrangements, by arranging the printing cylinders in such a manner that the printing cylinders which print conjointly, are brought into action simultaneously.

Preferably the arrangement is such that the printing cylinders are brought into position for printing before the actual printing takes place; that is to say, they are brought into position on the free edge of the print which remain unprinted, so that all shaking during the actual printing is entirely avoided. In the case of three color sheet intaglio printing machines preferably the first and third printing cylinders each begin to print on an impression surface simultaneously, while the second printing cylinder which is preferably arranged between them prints by itself. In four-color sheet

intaglio printing the first and third printing cylinders begin to print simultaneously each on an impression surface as do also the second and fourth, and in this case the second printing cylinder is advantageously arranged between the first and third printing cylinders; the printing by the second and fourth printing cylinders then takes place after or before the printing by the first and third printing cylinders.

According to a further development of the invention the printing cylinder system is so arranged relatively to the impression cylinder that the center of the printing cylinder system lies approximately in or somewhat below the horizontal plane containing the axis of the impression cylinder. By this means a position of the printing cylinder system is obtained whereby the path which the coloring fluid has to travel on the printing cylinder from the inking roller until it is applied, is relatively short, so that evaporation is reduced to a permissible degree. If the position of the printing cylinder is still lower the paths of the coloring fluid are further shortened, but the lowest printing cylinder in such case is situated in a position in which it is not accessible. On the other hand, if the printing cylinder system is raised so that its centre lies above the horizontal plane through the axis of the impression cylinder, the paths of the color during which evaporation takes place are lengthened to an extent which impairs the quality of the work.

Two embodiments of the invention, namely a three- and four-color sheet intaglio printing machine, are illustrated by way of example in the accompanying drawing in which

Fig. 1 is a diagrammatic illustration of the arrangement of the printing cylinders in a three color sheet intaglio printing machine,

Fig. 2 a diagrammatic illustration of the arrangement of the printing cylinders in a four color sheet intaglio printing machine again in accordance with the invention, and

Fig. 3 is a diagrammatic view showing the machine in greater detail and illustrating the operating mechanism for the printing

cylinders, the view being taken from the rear of Fig. 1.

Referring to Fig. 1 of the drawing, the impression cylinder a has four impression surfaces b_1, b_2, b_3 and b_4 . The beginning of each impression surface is displaced by an angle of 90° from the beginning of the next surface. According to the invention, the three printing cylinders c_1, c_2 and c_3 , the axes of which lie on an imaginary cylindrical surface concentric with the axis of the impression cylinder, are arranged in such a manner that the centres of the printing cylinders c_1 and c_3 lie on the arms of a quadrant of 90° , the apex of which coincides with the centre of the impression cylinder a . The arrangement is therefore such, that the printing cylinders c_1 and c_3 always face corresponding portions of two of the impression surfaces b_1 to b_4 , and these two printing cylinders are caused to move simultaneously toward the impression cylinder by means of any suitable mechanism and engage such cylinder at the same time, while the cylinder c_2 is separately brought to printing position and prints by itself.

I have found that particularly in a printing apparatus of such kind that the cylinders c_3 and c_1 are moved into printing position before the printing begins i. e. to the free edge of the sheet which remains unprinted, the unavoidable shaking of the impression cylinder a remains without effect. During the printing by the printing cylinders c_3 and c_1 no further shaking of the impression cylinder takes place. Only when the beginning of the impression surface b_2 is located by the printing cylinder c_2 does this cylinder begin to print, without the shaking which is caused thereby doing any harm because the printing cylinder c_2 prints by itself.

In Fig. 2 the impression cylinder A has five impression surfaces B_1, B_2, B_3, B_4 , and B_5 , the beginning of each of which is displaced by an angle of $\frac{360}{5} = 72^\circ$ from the next. According to the invention the four printing cylinders C_1, C_2, C_3 and C_4 , the axes of which lie along a cylindrical surface concentric with the axis of the impression cylinder, are so arranged that the centers of the printing cylinders C_1 and C_3 or of C_2 and C_4 , each lie on an arm or radius of a sector of 72° the apex of which coincides with the center of the impression cylinder A . The printing cylinder C_2 lies between the printing cylinders C_1 and C_3 . The cylinders C_1 and C_3 thus simultaneously engage the printing fields B_1 and B_5 and when they have finished their printing they are withdrawn; as soon as the advance edges of printing fields B_2 and B_4 reach a position opposite the printing cylinders C_2 and C_4 , respectively, these latter cylinders are simultaneously moved into printing position. Thus, no printing

cylinder is moved into printing position while another cylinder is printing, and consequently no jarring or vibration occurs while any cylinder prints.

I have found that, particularly in a printing apparatus of the kind such that the cylinders C_3 and C_1 or C_4 and C_2 are closed up before printing i. e. on to the free edge of the sheet which remains unprinted, the unavoidable shaking of the impression cylinder A remains entirely without effect. During printing by the printing cylinders C_3 and C_1 no further shaking of the impression cylinder A takes place. Only when the beginning of the impression surface B_2 is located in front of the printing cylinder C_4 and the beginning of the impression surface B_3 in front of the printing cylinder C_2 are the printing cylinders C_4 and C_2 closed up simultaneously, without the shaking caused thereby having any harmful effects.

In the forms of the invention shown in the drawing the printing cylinder system is so arranged relatively to the impression cylinder that the center of the printing cylinder system is somewhat below the horizontal plane through the axis of the impression cylinder. In this way an arrangement of the system of printing cylinders is obtained whereby the paths of the coloring fluid on the printing cylinders from the inking rollers to the line of contact with the impression cylinder are short, so that the color evaporates only slightly. By lowering the position of the printing cylinders the paths can be further shortened but the lowest printing cylinder is then in an inaccessible position. If the printing cylinder system is raised so that its center lies above the horizontal plane containing the axis of the impression cylinder the paths of the coloring fluid on the printing cylinder where evaporation occurs are lengthened so that the colors arrive at the place of application in a condition in which they have already begun to dry, with the result that a satisfactory print is not obtained. I have found that optimum conditions prevail when the center of the impression cylinder, the center of the lowest of the three printing cylinders and the center of the inking roller belonging to such lowest printing cylinder all lie in a straight line or nearly so, so that the shortest path for the coloring fluid on the printing cylinder from the inking roller to the point of application on the impression cylinder is provided, without bringing the lowest printing cylinder into an inaccessible position.

Fig. 3 shows diagrammatically the mechanism for operating the printing cylinders c_1, c_2, c_3 , the scrapers of the printing cylinders being indicated by the characters d_1, d_2, d_3 . The color troughs are shown at f_1, f_2, f_3 ; while the color rollers are indicated by the letters e_1, e_2, e_3 . The printing cylinders and

their scrapers, color troughs and color rollers are mounted upon lateral carrying frames h_1, h_2, h_3 , which are rotatably mounted in the frame Z of the machine, as shown at g_1, g_2, g_3 , respectively.

5 The printing cylinders are moved toward and away from the impression cylinder a in the following manner. The printing cylinders c_1, c_3 , or their drives are so coupled that they begin to print simultaneously. A guide k_1 engages the pivot i_1 of the frame h_1 , such 10 guide being articulated to the crank l_1 , as shown at m_1 . The crank is formed by one arm of a two-armed lever l_1, l_1' which is pivoted at n_1 . The arm l_1 is connected with the 15 arm l_3'' of the double lever l_3'', l_3' by the coupling rod o_1, s . The arm l_3' is connected with an oscillating lever q_1, s by a coupling rod p_1, s , such lever being joined through its other end 20 with a link r_1, s which is in turn connected with a sharp-angled lever s_1, s . The latter is pivoted in the frame of the machine at t ; its free arm carries a roller v_1, s which bears 25 against the cam u . Through the mechanism just described the cam u controls the double levers l_1', l_1 and l_3', l_3 . The oscillating movement 30 of these double levers is transmitted to the frames h_1 and h_3 through the guides k_1 and k_3 and through such frames to the printing cylinders c_1 and c_3 , so that the latter begin to print or cease to print upon the different printing surfaces of the impression cylinder at the proper instants according to the form of the cam u .

35 The cylinder c_2 is controlled in a similar fashion. A guide k_2 is pivoted to the frame h_2 at i_2 , while the frame itself is pivoted at q_2 . The guide k_2 is pivoted to the crank arm l_2 of a double-armed lever l_2, l_2' at m_2 , said 40 lever being rotatably mounted at n_2 in the frame Z of the machine. The arm l_2' is connected through a coupling rod o_2 with a double lever p_2 which is pivoted at q_2 in the machine frame. The other arm of such lever 45 is controlled through a rod r_2 by a double lever s_2 rotatably mounted at t_2 in the machine frame. The horizontal arm of this double lever is connected by a link v_2 with a bell-crank lever w_2 at w_2 , the latter lever 50 being oscillatable about the axis y_2 . The free arm of lever w_2 carries a roller z_2 which engages the cam u . The cam is rotated by a shaft W which is geared to the driving 55 motor of the machine. The arrangement of the printing cylinders and cam is such that the novel operations above described, namely, the simultaneous beginning of printing of the cylinders which print together, are obtained.

60 I claim:

1. In a multi-color sheet intaglio printing machine, the combination of an impression cylinder having more than two printing surfaces thereon, more than two printing cylinders whose axes lie upon an imaginary cylin-

der concentric with the axis of the impression cylinder, mechanism operative upon at least two, but less than all, of said printing cylinders to move the same simultaneously against different printing surfaces while the other 70 printing cylinder or cylinders are in non-printing position, and means for moving the other printing cylinder or cylinders into printing position while the first-mentioned printing cylinders are in non-printing position, 75 so that no printing is being performed as a simultaneously controlled group of cylinders or a single cylinder is moved into printing position against the impression cylinder. 80

2. In a three color sheet intaglio printing machine, the combination of an impression cylinder having four printing surfaces thereon, three printing cylinders whose axes lie upon an imaginary cylinder concentric with the axis of the impression cylinder, mechanism operative upon two of the printing cylinders to move the same simultaneously against different printing surfaces while the third printing cylinder is in non-printing 90 position, and means for moving said third printing cylinder toward said impression cylinder after the two first-mentioned cylinders have finished printing, whereby the disturbing effect of vibration is eliminated. 95

3. In a three color sheet intaglio printing machine, the combination of an impression cylinder having four printing surfaces thereon, three printing cylinders whose axes lie upon an imaginary cylinder concentric with the axis of the impression cylinder, mechanism operative upon two of the printing cylinders to move the same simultaneously against different printing surfaces while the third printing cylinder is in non-printing 100 position, and means for moving said third printing cylinder toward said impression cylinder after the two first-mentioned cylinders have finished printing, whereby the disturbing effect of vibration is eliminated, the third 105 printing cylinder being arranged between the two first-mentioned printing cylinders. 110

4. The combination as set forth in claim 1, wherein the center of the printing cylinder system lies in or below the horizontal plane 115 passing through the axis of the impression cylinder.

5. The combination as set forth in claim 2, including inking rollers associated with said printing cylinders, the centers of the 120 axes of the impression cylinder, the lowest printing cylinder and its associated inking roller lying along a straight or an approximately straight line.

In testimony whereof I have hereunto set 125 my hand.

ARNOLD AUGUST EGLI.
